US00D746747S

(12) **United States Design Patent**
Shapiro et al.

(10) **Patent No.:** **US D746,747 S**
(45) **Date of Patent:** ** **Jan. 5, 2016**

(54) **FLIGHT CONTROL PANEL**

(71) Applicants: **Geoffrey A. Shapiro**, Cedar Rapids, IA (US); **Timothy J. Etherington**, Hampton, VA (US); **Laura Maxine Smith-Velazquez**, Owings Mills, MD (US)

(72) Inventors: **Geoffrey A. Shapiro**, Cedar Rapids, IA (US); **Timothy J. Etherington**, Hampton, VA (US); **Laura Maxine Smith-Velazquez**, Owings Mills, MD (US)

(73) Assignee: **Rockwell Collins, Inc.**, Cedar Rapids, IA (US)

(**) Term: **14 Years**

(21) Appl. No.: **29/468,159**

(22) Filed: **Sep. 26, 2013**

(51) LOC (10) Cl. **12-16**
